PROPELLION SCREW

Filed Feb. 27, 1928

FIG. 1

FIG. 2

Inventor:
Friedrich Tismer

By Louis Daniels
Attorney

UNITED STATES PATENT OFFICE.

FRIEDRICH TISMER, OF BERLIN, GERMANY.

PROPELLION SCREW.

Application filed February 27, 1928, Serial No. 257,473, and in Great Britain February 3, 1928.

This invention relates in general to propellers and screws of the kind employed on air and water craft and is concerned more particularly with propellers and screws of the type provided with so-called nozzle or slot devices, that is, screws the blades of which are provided with nozzle-like orifices or passages or with nozzle-like slots or grooves at the trailing edges or are furnished with both 10 these devices.

According to the present invention, the object of which is to improve the properties of screws of this type, provision is made of a plurality of grooves or slots running through 15 or over the trailing edges of the blades from the higher pressure side to the lower pressure side of the blades and tapering or narrowing down in cross-section from said higher pressure to said lower pressure side, or of completely enclosed passages or orifices tapering 20 similarly to the grooves but located in a position forwardly of the trailing edges. If necessary both devices may be employed together on the same screw. These devices 25 exercise nozzle like effects on the air or other medium and facilitate the pressure compensation or equilization at the trailing edges of the screw.

Screws with slots at the trailing edges of 30 the blades are already known but in these known screws the slots flare outwardly from the forward edges to the rearward edges of the blades. Furthermore air screws are known wherein the blades are interrupted, the 35 interruptions being either very wide and thus allowing the passage of a considerable amount of air or flared outwardly from the higher pressure side to the lower pressure side. Finally supporting surfaces for air craft are 40 also known which have longitudinal slots at the leading wing edge whereby the profile of the surface is subdivided into a number of separate profiles disposed one behind the other in a louvre-like arrangement.

By way of example the application of the invention to an air craft propeller or air-screw is illustrated diagrammatically in the accompanying drawing in which:

Fig. 1 is a cross-section of the air-screw on 50 the line A—B of Fig. 2, and

Fig. 2 shows a part of the air-screw in side elevation.

In the drawing the reference letter *a* indicates the air-screw blade, *b* the high pressure side thereof, *c* the lower pressure side, *d* the 55 openings on the high pressure side and *e* the openings on the lower pressure side of passages *i* tapering according to the invention, *f* the portion on the high pressure side of similarly tapering grooves, *g* the portion on the 60 low pressure side thereof and *h* the trailing edge of the air-screw blade.

The bores or passages and the slots or grooves which taper from the high pressure side to the low pressure side of the blade may 65 be given a twist or made helical to conform with the air or other flow and their cross-sections may be of various shapes. The cross-section of the bores or passages may be round, 70 oval or oblong and that of the grooves rectangular, triangular, trough-shaped or the like. The screw may be constructed with grooved or slotted metal members mounted on the trailing edges of the blades and the bores may be lined if necessary.

Provision may also be made for opening and closing or constricting the bores and grooves, this may be effected automatically, for example with the aid of centrifugal force, or arbitrarily by manual or mechanical operation.

What I claim is:—

1. In a propulsio screw the combination with a blade for the purpose of facilitating pressure equilization between the two sides of the trailing edge of said blade of passages associated with said trailing edge and tapering from the higher pressure side to the lower pressure side thereof, said passages being angularly arranged relative to the width of 85 the blade.

2. In combination with the blades of a propulsio screw, surface passages formed across the trailing edges of said blades and tapering from the higher pressure side to 95 the lower pressure side thereof, said passages being angularly arranged relative to the width of the blade.

3. In combination with the blades of a propulsio screw, nozzle-like passages tapering 100

from the higher pressure side to the lower pressure side of the blades and formed in the trailing edges of said blades, said passages being angularly arranged relative to the width 5 of the blade.

4. In a propulsion screw, the combination with a blade of two series of passages tapering from the higher pressure side to the lower

pressure side thereof, one series being formed across the trailing edge of said blade and the 10 other through the blade in proximity to said edge, said passages being angularly arranged relative to the width of the blade.

In testimony whereof I hereunto affix my signature this 13 day of February, 1928.

FRIEDRICH TISMER.
